(57) **CLAIM**

The ornamental design for a ride-on vehicle, as shown and described.

DESCRIPTION

FIG. 1 is a front view of a ride-on vehicle.

FIG. 2 is a back view of the ride-on vehicle.

FIG. 3 is a right side view of the ride-on vehicle.

FIG. 4 is a left side view of the ride-on vehicle.

FIG. 5 is a top view of the ride-on vehicle.

FIG. 6 is a bottom view of the ride-on vehicle; and,

FIG. 7 is a front perspective view of the ride-on vehicle. The broken lines showing in the Figures are for the purpose of illustrating unclaimed portions and form no part of the claimed design.
